INVENTOR.
Robert Gooden

BY

Geo. P. Kimmel. ATTORNEY.

UNITED STATES PATENT OFFICE.

ROBERT GOODEN, OF OELWEIN, IOWA.

LIGHT SHADE.

Application filed October 27, 1923. Serial No. 671,160.

To all whom it may concern:

Be it known that I, ROBERT GOODEN, a citizen of the United States, residing at Oelwein, in the county of Fayette and State 5 of Iowa, have invented certain new and useful Improvements in a Light Shade, of which the following is a specification.

This invention relates to electric lamp shades and has for its primary object the 10 provision, in a manner as hereinafter set forth, of a shade adapted to be secured to the socket carrying the lamp and so constructed as to allow its being freely revolved about the lamp.

15 The invention broadly comprises a collar portion and a light deflecting element, the collar portion adapted to be clamped about the socket of an electric lamp and having one end, its forward end, enlarged to receive an annular constricted portion of the light deflecting element therein, the enlarged collar portion and the constricted portion of the light deflecting element being formed to provide a ball bearing connection 20 between the two elements.

25 Another object of the invention is the provision, in a manner as hereinafter set forth, of a revoluble electric lamp shade of light but durable construction, attractive in 30 appearance, and inexpensive to manufacture.

The invention will be best understood from a consideration of the following detailed description taken in connection with the accompanying drawings forming part of 35 this specification, with the understanding that the invention is not confined to any strict conformity with the showing of the drawings, but may be changed and modified so long as such changes and modifications 40 mark no material departure from the salient features of the invention as expressed in the appended claims.

In the drawings:

45 Figure 1 is a vertical longitudinal sectional view of the device embodying this invention, shown as applied to a lamp socket.

Fig. 2 is a vertical longitudinal section of the shade portion.

Fig. 3 is a detail of the collar portion.

50 Fig. 4 is a section taken on the line 4—4 of Fig. 2, and

Fig. 5 is a section taken on the line 5—5 of Fig. 3.

55 Referring now to the drawings in detail, wherein like numerals of reference indicate corresponding parts throughout the several

views of the drawing, a lamp socket is indicated at 1 having the usual shoulder at the rear part 1' and carrying a lamp 2, this structure being of the usual design and forming no part of the present invention.

The structure embodying this invention comprises a collar member 3 having the end 4 formed of a proper diameter to fit about the socket 1 and having its central portion provided with an outstanding flange 5 which merges into the enlarged outer end 6 having in its central portion the annular ball race 7 and terminating in the annular outstanding flange 8. This collar is split 70 throughout its entire length as indicated clearly at 9 in Fig. 3, and the inner portion 4 is provided upon either side of the division 9 with opposed ear members 10 having threaded apertures therethrough to receive 75 a thumb screw 11 whereby the ear members may be drawn together and the collar tightened about the socket of the lamp.

Carried by the collar 3 is a light deflecting element 12 having a constricted portion 13 and terminating in the annular ring 14 which is of substantially the same width as the portion 6, and is provided with the encircling ball race 15 in its outer surface.

As clearly shown in Fig. 1, the ring 14 is 80 adapted to fit within the portion 6 and when in position, the race 15 is aligned with the race 7 in the portion 6 to receive therein the balls 16.

The ring 14 is of slightly greater diameter 90 than the socket 1, and when placed within the collar and the collar placed upon the socket 1, the screw 11 is tightened, drawing in the inner portion 4 tightly about the socket and causing the outer portion to close 95 sufficiently tight to hold the light deflecting element in proper position, but not clamped too tightly about the lamp to prevent its being turned within the collar.

What I claim is:

1. In a lamp shade, a split collar adapted to be positioned about a lamp socket, means carried by said collar for tightening the same about the lamp socket, a light deflecting element having means for connection with said clamp, and a ball bearing coupling said clamp and said connecting means.

2. In a lamp shade, a split collar adapted to encircle a lamp socket, opposed outstanding ears positioned one on each side of the 110 said split portion, screw means connecting said ears for drawing said portions together,

- a light deflecting element having means for connection with said clamp, and a ball bearing coupling said clamp and said connecting means.
5. 3. In a lamp shade, a split lamp socket engaging collar of greater diameter at one end than at the other and having an annular flange at its central part connecting the part of one diameter with that of the other, opposed outstanding ears positioned one on each side of said split portion, screw means connecting said ears and adapted to draw said portions together, said part of large diameter having a ball race pressed in its inner surface, and a light deflecting element having one end constricted and formed to provide an annular ring having a ball race formed in its outer surface to cooperate with said first mentioned ball race, said ring being adapted to revolve within said part of large diameter upon balls positioned within said cooperating races.
10. 4. In a lamp shade, a split lamp socket engaging collar of greater diameter at one end than at the other and having an annular flange at its central part connecting the part of one diameter with that of the other, opposed outstanding ears positioned one on each side of said split portion, screw means connecting said ears and adapted to draw said portions together, a light deflecting element having means for connection with said clamp, and a ball bearing coupling said clamp and said connecting means.
15. 4. In a lamp shade, a split lamp socket engaging collar of greater diameter at one end than at the other and having an annular flange at its central part connecting the part of one diameter with that of the other, opposed outstanding ears positioned one on each side of each split portion, screw means connecting said ears and adapted to draw said portions together, said part of large diameter having a ball race pressed in its inner surface, and a light deflecting element having one end constricted and formed to provide an annular ring having a ball race formed in its outer surface to cooperate with said first mentioned ball race, said ring being adapted to revolve within said part of large diameter upon balls positioned within said cooperating races.

In testimony whereof, I affix my signature hereto.

ROBERT GOODEN.
